UNITED STATES PATENT OFFICE.

ALEXANDER ALMASY, OF CHROME, NEW JERSEY.

DESIGN FOR A CURTAIN-FIXTURE.

46,937.

Specification for Design.

Patented Feb. 16, 1915.

Application filed December 23, 1914. Serial No. 878,817. Term of patent 14 years.

To all whom it may concern:

Be it known that I, ALEXANDER ALMASY, a citizen of the United States, residing at Chrome, in the county of Middlesex and State of New Jersey, have invented a new, original, and ornamental Design for Curtain-Fixtures, of which the following is a specification.

Reference is had to the accompanying drawing, in which:

Figure 1 is a side elevation of a curtain fixture showing my new and ornamental design. Fig. 2 is a plan view of the same.

Copies of this patent may be obtained for five cents each, by addressing the "Commissioner of Patents, Washington, D. C."

What is claimed is:

The ornamental design for a curtain fixture, substantially as shown.

In testimony, that I claim the foregoing as my own, I have hereto affixed my signature in the presence of two witnesses.
